UNITED STATES PATENT OFFICE

137,614

DESIGN FOR A SWITCH BRACKET

Oscar H. Kaminky, Freeport, Ill., assignor to Micro Switch Corporation, Freeport, Ill., a corporation of Illinois

Application December 6, 1943, Serial No. 111,936

Term of patent 7 years

(Cl. D26—13)

To all whom it may concern:

Be it known that I, Oscar H. Kaminky, a citizen of the United States, residing at Freeport, in the county of Stephenson and State of Illinois, have invented a new, original, and ornamental Design for a Switch Bracket, of which the following is a specification, reference being had to the accompanying drawing, forming part thereof.

In the drawing:

Fig. 2 is a side view;
Fig. 3 is an end view thereof; and
Fig. 4 is a top view.

The dominant feature of my design resides in the portion shown in full lines.

I claim:

The ornamental design for a switch bracket, substantially as shown and described.

OSCAR H. KAMINKY.
